UNITED STATES PATENT OFFICE.

JOHN WILLIAM SNAPE, OF EDMONTON, ALBERTA, CANADA, ASSIGNOR OF FORTY PER CENT TO GEORGE FREDERICK MOHLMAN, OF EDMONTON, CANADA.

VARNISH.

No Drawing.

Application filed April 16, 1923. Serial No. 632,526.

To all whom it may concern:

Be it known that I, JOHN WILLIAM SNAPE, a subject of the King of Great Britain, and residing at the city of Edmonton, in the Province of Alberta, in the Dominion of Canada, have invented a new and useful Improvement in Varnishes, of which the following is the specification.

The object of my invention is the production of a varnish that can be applied as a covering over any painted or unpainted wood or iron work or other material, acting as a preservative and making them impervious to the weather or other destructive agents.

My composition consists of the following ingredients, mixed in the quantities approximately as shown.

For one quart:—two ounces of clear celluloid, two drams of spirits of camphor, ten ounces of methylated spirits, thirty ounces of acetone and from one to one and a half drams of domestic castor oil.

The ingredients in this formula will produce a clear, colorless and transparent varnish, that will withstand the severest weather. It is waterproof, air-proof and acid-proof and will resist the penetrating powers of muriatic acid, also sulphuric acid to the strength as used in storage batteries and accumulators. It will prevent the acid creeping from the batteries of an automobile, along the channel of the chassis to the body work, which would destroy the paint and varnish and hasten corrosion.

It makes a lasting varnish for highly polished surfaces such as table tops, automobile bodies, etc., and is not affected by mud, wind or rain.

It is a very sanitary covering for a bathroom, washhouse, toilet or lavatory and has a very pleasing effect over any paint or enamel, being washable without destroying its lustre.

It can also be used as a varnish for oil paintings, photographs, etc., acting as a preservative.

It forms a good covering for buildings, bridges and other structures of wood, iron or steel, keeping the weather and chemical laden air from attacking and rotting them.

It is crystal clear, closely adherent and flexible, and can be washed with hot water or strong washing compounds, such as ammonia, without the slightest injury to the lustre or surface.

What I claim as my invention is:

The combination of the following ingredients mixed in suitable proportions as specified:—clear celluloid, spirits of camphor, methylated spirits, acetone and domestic castor oil.

Signed at the city of Edmonton, this 4th day of April, 1923.

JOHN WILLIAM SNAPE. [L. s.]

In the presence of—
GLADYS CUFF,
J. J. DOUGHERTY.
